(57) **CLAIM**

The ornamental design for a bottle, as shown and described.

DESCRIPTION

FIG. 1 is a first perspective view of a bottle showing my new design;

FIG. 2 is a second perspective view thereof;

FIG. 3 is a front side view thereof;

FIG. 4 is a rear side view thereof;

FIG. 5 is a top view thereof;

FIG. 6 is a bottom view thereof;

FIG. 7 is a left side view thereof;

FIG. 8 is a right side view thereof; and,

FIG. 9 is a sectional view thereof, as designated by the dash-dot line in FIG. 3.

The evenly broken lines shown in FIGS. 2 and 6 are shown for the purpose of illustrating parts of the article that form no part of the claim. The dot-dash broken lines represent the origin of the cross-sectional view of FIG. 9 and form no part of the claim.

1 Claim, 9 Drawing Sheets
